UNITED STATES PATENT OFFICE.

THOMAS L. LUDERS, OF PHILADELPHIA, PA., ASSIGNOR OF ONE-HALF OF HIS RIGHT TO CHARLES J. A. DICK, OF LONDON, ENGLAND.

CAR-AXLE BOX.

SPECIFICATION forming part of Letters Patent No. 228,657, dated June 8, 1880.

Application filed March 29, 1880. (No model.)

To all whom it may concern:

Be it known that I, THOMAS L. LUDERS, a citizen of the United States, residing in Philadelphia, Pennsylvania, have invented an Improvement in Axle-Boxes, of which the following is a specification.

The main object of my invention is to combine with an axle-box pumping mechanism, substantially as described hereinafter, whereby the oil which has fallen from the journal or bearing of the box may be raised and discharged against the journal or bearing when the car, locomotive, or tender to which the box appertains is in motion, the operation of the pump being due to the movement of the box in its guides.

In the accompanying drawings, Figure 1 is a vertical section of an axle-box with my self-lubricating device applied thereto; Fig. 2, a transverse section on the line 1 2; Fig. 3, a plan view of the pumping mechanism, and Figs. 4 and 5 views illustrating the mode of making the valves of a pump which may be advantageously employed.

The axle-box A is of the usual construction, and is furnished with the ordinary bearing B for the journal d of the axle D.

In the interior of the box, and to one side of the same, is pivoted a weighted arm, G, by a stud, b, and this arm is acted on by a spiral spring, h. The arm remains in a quiescent condition as long as the car to which the axle-box appertains is stationary; but when the car is in motion there must always be more or less vertical movement of the box in its guides, and there must consequently be more or less vibration of the arm on its pivot-pin. By the combination of this weighted arm with pumping appliances the oil which falls from the journal and bearing into the bottom of the box is raised and reapplied to the journal, which is thus constantly maintained in a thoroughly lubricated condition when proper lubrication is most essential—that is, when the car is in motion.

Different kinds of pumping devices will readily suggest themselves to an expert mechanic; but I believe that the appliances which I will proceed to describe are the most simple and economical, and will perform their

duties quite as well as more costly mechanism.

The pump itself consists of two disks, m and n, of leather, properly secured together near their edges, the lower disk being secured at its center to the bottom of the axle-box, preferably by a bolt passed from below the box through an opening in the same and adapted to a nut on the said lower disk.

A force-pipe, p, extends upward from the upper disk, m, of the pump, and terminates at such a point that the oil will be discharged from it against the journal of the axle immediately below the edge of the bearing.

Suction-valves are formed in the lower disk, n, and a discharge-valve in the upper disk, m, preferably in the manner best observed in Figs. 4 and 5.

Where a valve has to be formed in the leather an incision is made through the same, preferably of the segmental form shown in Fig. 4, the portion of the leather bounded by the incision becoming a flap-valve, connected to the disk by the uncut portion of the leather, but free to open and close, the incision being made in the inclined course shown in Fig. 5, so that there will be a beveled seat on the edge of the opening in the leather for the beveled edge of the valve. There is a single discharge-valve, q, of this character in the center of the upper disk, where the force-pipe p is connected to the same. The lower disk has suction-valves, (two in the present instance,) one on each side of the bolt which secures it to the bottom of the box.

The pipe p is secured to and moves with the weighted arm. In other words, the pipe is the pump-rod by which the weighted arm is connected to the upper disk of the pump, simplicity in construction being attained by this arrangement.

A force-pump of the ordinary character may be substituted for the leather pump; but the latter is the more economical and will perform the desired duty quite as well as more costly pumping appliances.

I prefer to filter the oil which drops from the journal and bearing before it reaches the pump, for which purpose I use cotton-waste or other absorbent filtering medium placed be-

tween the bottom of the box and a removable 5
perforated plate or plates, H, the pump being
contained within a well, W, which is bounded
on one side by a side of the box, and on the
three remaining sides by vertical perforated
plates I, and this well may be covered, so that
all the oil from the journal and bearing must
pass through the waste before it can gain ac-
cess to the pump.

- 10 The pipe *p* may have a branch, (shown by
dotted lines in Fig. 2,) so that oil may be dis-
charged against the journal in opposite direc-
tions, in which case there will always be a
supply of oil to be conveyed by the journal
15 directly to its bearing, whichever of the two
directions the journal may revolve in; or, if
desired, the box may contain two pumps, each
furnished with the actuating appliances de-
scribed, one pump discharging oil against one
20 side of the journal and the other pump forc-
ing the oil against the opposite side of the
same.

25 My invention, although especially applica-
ble to the axle-boxes of cars, locomotives, and
tenders, may be adapted to any bearings which
are so moved or agitated as to impart a vi-
brating motion to a weighted arm.

It is not essential that the spring *h* should
30 be situated at the point shown; but the spring,
wherever it is located, should be such in rela-
tion to the weight exerted on the spring that
the latter will balance the former, and a column
35 of oil will extend from the pump to the outlet
of the force-pipe when the box is in a quies-
cent state, so that the first movement imparted
to the weighted arm will be at once followed
by the discharge of oil against the journal.

If desired, the oil may be discharged at such
40 a point that it will pass through a channel in
the bearing to the journal.

When it is not desired to rely altogether on
the inertia of a weighted arm, G, to effect the
operation of the pump, a rod (shown by dotted

lines in Fig. 1) may extend from the lever, or
from the pump itself, through an opening in 45
the top of the box, the end of this rod being
arranged to come in contact with a portion of
the fixed frame in which the box is guided, so
that as said box moves in its guides a posi-
tive movement will be imparted to the arm G 50
or to the upper disk or piston of the pump.
In other words, instead of the pump-operating
device being contained entirely within the box
and acting by inertia, it may extend beyond
the box and be acted upon by a portion of 55
the fixed frame. The arrangement shown, how-
ever, is preferred, as it is simple in construc-
tion, effective in operation, and does not ne-
cessitate the formation in the casing of the box
of openings, through which dust or moisture 60
can enter.

I claim as my invention—

1. The combination, in an axle-box, of a bal-
anced and weighted arm pivoted to the said
box, with a pump actuated by the said arm, 65
and with a pipe through which oil may be
forced by the pump against the journal or to
a point above the same, substantially as set
forth.

2. The combination, in an axle-box, of a 70
weighted and balanced arm and a pump actu-
ated by the said arm, with a well, W, formed
in the bottom of the box and bounded by per-
forated plates, substantially as described.

3. The combination, in an axle-box, of the 75
weighted and balanced arm, a pump com-
posed of two flexible disks, and a force-pipe
connected to the said arm and to one of the
disks, substantially as set forth.

In testimony whereof I have signed my 80
name to this specification in the presence of
two subscribing witnesses.

THOS. L. LUDERS.
